UNITED STATES PATENT OFFICE

168,003

ATOMIZER

Carl W. Sundberg, Birmingham, Mich., assignor
to The De Vilbiss Company, Toledo, Ohio, a
corporation of Ohio

Application June 28, 1952, Serial No. 20,390

Term of patent 14 years

(CL. D83—1)

To all whom it may concern:

Be it known that I, Carl W. Sundberg, a citizen
of the United States, residing at 1260 Lynhurst
Road, Birmingham, in the county of Oakland
and State of Michigan, have invented a new,
original, and ornamental Design for an Atomizer,
of which the following is a specification, refer-
ence being had to the accompanying drawing,
forming part thereof.

In the drawing:

Fig. 1 is a front elevational view of an atomizer
showing my new design; and Fig. 2 is a side elev-
ation thereof.

The essential feature of my new design resides
in the portions shown in full lines.

I claim:

The ornamental design for an atomizer, as
shown and described.

CARL W. SUNDBERG.
